UNITED STATES PATENT OFFICE.

JOHN FRANCIS BOORAEM, OF NEW YORK, N. Y.

WALL CONSTRUCTION.

Application filed October 15, 1920. Serial No. 417,270.

To all whom it may concern:

Be it known that I, JOHN FRANCIS BOORAEM, a citizen of the United States, and a resident of the city of New York, State of New York, have invented certain new and useful Improvements in Wall Construction, of which the following is a description.

The present invention relates to improvements in wall construction and has specific relation to walls wherein the inner exposed surface is desired to be had in the form of a veneer of marble, glass, tile, terra cotta, enameled brick or the like, to provide a glossy, non-absorbent and sanitary finish.

The general objects of the invention are, first, to provide in a wall of the above type, a construction which will not sweat or condense the moisture in atmospheric air under conditions where the opposite faces of the wall are exposed to different temperatures, and, secondly, to prevent chipping, cracking or dislodgement of sections of the veneer by pressure acting from behind the sections, and resulting from conditions where either face of the wall is from time to time exposed to the pressure of a hydrostatic head, operating exteriorly of the wall to force liquid either through the joints between the sections of veneering or through the retaining wall and into the voids behind the sections.

To these ends the invention resides in providing a wall of the type hereinbefore mentioned with a prescribed system of conduits, disposed between the veneering and retaining wall and arranged in operative relation to a source of fluid supply, which in one form of the invention will operate to circulate a heating agent through the conduits to prevent sweating of the exposed surface of the veneering, under conditions when the opposite faces of the wall are simultaneously exposed to different temperature; or, in another form of the invention, the conduits may function to circulate a drying medium which in instances where the veneering forms the lining of water reservoirs, such as swimming pools, will operate to dry the joints between the sections of veneering when the pool is empty; or, in a further form of the invention the conduits may effect the maintenance of a hydrostatic balance on the opposite faces of the veneering when the same forms the lining of

a swimming pool; and, still further the conduits may act as a drain to carry all liquid entering the wall by percolating through the joints of the veneering or through the retaining wall.

Other objects will appear and be better understood from that embodiment of the invention of which the following is a specification, reference being had to the accompanying drawing, forming part thereof and in which:

Figure 1 is a fragmentary perspective of a wall constructed in accordance with this invention;

Figure 2 is a view, in fragmentary perspective, of one form of the invention applied to a swimming pool;

Figure 3 is a fragmentary perspective of the inlet end portion of the pool shown in Figure 2;

Figure 4 is a view similar to Figure 3 but showing the fluid supply system partly in section and partly diagrammatic;

Figure 5 is a diagrammatic plan of a swimming pool provided with my invention;

Figure 6 is a longitudinal sectional view of Figure 5;

Figure 7 is a detail perspective of one of the ceramic veneering sections;

Figure 8 is a view similar to Figure 5 of another form of veneering section;

Figure 9 is a view similar to Figure 5 of a modified form of veneering section;

Figure 10 is a detail perspective of a modified form of veneering section;

Figure 11 is a detail perspective partly in section of the floor drain or trap of the pool shown in Figure 5;

Figure 12 is a detail plan of Figure 11;

Figure 13 is a cross section on line B—B of Figure 12;

Figure 14 is a cross section on line A—A of Fig. 12; and

Figure 15 is a detail perspective of a modified form of wall constructed of enameled brick.

The wall designated generally by *a* in the drawing may form one of the walls of an ordinary building, vault, underground railway station or the like, or as shown in Figures 2 and 3, said wall may be the enclosing wall of an ordinary swimming pool. The body 5 of wall *a* may be constructed in accordance with

any method and formed of any of the materials generally used for such purposes, such as wood, plaster, metal, ceramic bodies or concrete. As shown, the body is composed of 5 concrete. The section *b* of veneering may be glass, marble, tile, terra cotta, enameled brick or any combination of these, as for instance, terra cotta and tile, or enameled brick and terra cotta, as shown in the drawing.

10 In constructing the wall of this invention for the purpose of effecting drainage, drying, hydrostatic balance or the prevention of sweating, or any combination of these according as the requirements of the structure 15 demand, the blocks of veneering are so formed and laid as to provide a series of conduits 6, interposed between the exposed surface of the veneering *b* and the body 5 of the wall. The conduits in the veneering may be arranged 20 in parallel rows, extending vertically, horizontally or in various directions intermediate between the vertical and horizontal in the same or different walls as required or found necessary and as shown in the drawing.

25 Where it is proposed simply to prevent sweating in the wall of an ordinary building, the conduits 6 may extend horizontally and may be placed in fluid communication 30 with outlets arranged at suitable intervals in the base of the veneering to establish connection between the interior enclosed by the wall and the conduits; in like manner inlet openings may be provided in the upper portion 35 of the wall. The outlets in the base of the veneering are designated in Figure 1 by the numeral 7. It will also be observed by reference to Figure 1 that the various rows 40 of conduits 6 intercommunicate through the vertical openings 7'. The provision of this construction operates to permit air from the space surrounded by the wall to circulate through the conduits 6, bearing in mind that air enters through the upper inlet openings 45 and on cooling descends and issues from the lower outlet openings 7. The air in circulating goes through the various rows of conduits 6 and from one into the other through the openings 7'. In this way corresponding 50 temperatures are maintained on opposite faces of the veneering and the veneering is insulated from the main body 5 of the wall. Obviously, under these conditions, corresponding temperatures are maintained 55 on the opposite faces of the veneering *b*, thus preventing cooling of the veneering below the temperature of the air in the space surrounded by the wall. Consequently, atmospheric 60 moisture in the space surrounded by the wall cannot condense on the exposed surface of the veneering.

65 The structure just described may also be used to advantage in the construction of the walls of underground railway stations, vaults, and the like, which are usually exposed to the

action of surface water percolating through the body 5 and which has heretofore caused dislodgement, cracking and chipping of the sections by erecting a hydrostatic head in the voids behind the sections. With the 70 present construction it will be obvious that water entering the conduits by percolating through the body 5 will be conveyed to the outlets 7, or their equivalents, disposed in suitable locations.

75 Where it is proposed that the conduits 6 serve as a means for circulating an agent designed to effect drying of the veneering and the joints between the sections thereof, as would be required in the case of outdoor or 80 indoor swimming pools, or in other types of water reservoirs, the general arrangement of parts heretofore named may be employed.

85 In Figures 2 to 6 a swimming pool is shown having walls embodying this invention. Each of the conduits 6 of the side walls 8 extends for the length of the corresponding section of the side walls, as determined by the slope of the floor 9, and the series of conduits 6 extends from the latter to the life rail 10, the said conduits being disposed in rows parallel with the courses of veneering *b*. At the deep end portion 11 of the pool, conduits 6 communicate with the distributing conduits 12 of the end wall 13, which diverge from the upper portion of wall 13, and connect with laterals 14, which form continuations of the conduits 6 of side walls 8. The openings indicated by 7 in Figure 1, are disposed for suitable distances apart at the base of the side and end walls, and thereby admit water to the conduits from the interior of the pool. With this construction it is obvious that the height of the water column in the pool and that behind the sections *b* of veneering will, at all times, correspond so that a hydrostatic balance will be maintained on the opposite faces of sections *b*. The sections *b* are united by ordinary cement. It is well known that the hydrostatic pressure of the liquid in a pool, as heretofore constructed and lined with a veneering of tile, enameled brick, glass, terra cotta, marble or the like, forces liquid into the joints between the sections of veneering. In variably voids will exist behind the sections and the liquid entering such voids erects an internal hydrostatic head. When the pool is empty it is obvious that the water constituting the head cannot escape except by the slow process of percolating through the joints.

110 Where several of these joints intercommunicate and are disposed one above the other a formidable head results. The pressure of such a head is frequently evidenced by the bulging of sections of the veneering near the base of the head and the cracking, chipping, or total displacement of the said sections. The foregoing is particularly true 115

- in the case of outdoor pools erected in localities where freezing temperature is had during winter, when the pool is empty. Under these conditions the expansive force of the water entrapped between the veneering and the body of the wall, on freezing operates over a relatively large area of the veneering and causes considerable damage thereto. With the construction thus far described, it is obvious that an internal hydrostatic head cannot be maintained when the pool is empty, because of the drainage facilities afforded by the conduits.
- Referring now to the drawings, a source of heat supply 15, herein shown, as a plurality of coils of pipe through which steam is circulated by a suitable generator as a steam boiler, not shown, is located in a chamber 16 formed of any suitable material as metal and connected at one end with a series of vertical ducts 17, disposed transversely of the end wall 13 and communicating with the upper ends of the diverging conduits 12 and the vertical conduits 12'. A blower 18, which may be electrically operated, forces heated air around the coils 15 through the ducts 17 and conduits 12, 12', 14 and 6 and finally through the conduits 20 in the end wall 21 at the shallow portion 22 of the pool. From the conduits 20, which may be disposed similarly to the conduits 12', the heated air passes into a recess 23 disposed above the water line of the pool in the end wall 21 and then into the atmosphere. The portion of the chamber 16 in which the blowers are disposed is relatively deep and is closed on four sides by the bottom wall 24, top wall 25 and the side walls 26. The top wall 25 is practically flush with the top of the pool, and the inner section 27 of the bottom wall 24 inclines upwardly so that the throat 17 is relatively shallow. The inner sections 28 of the side walls 26 are flared outwardly toward the throat 17 and the area of the latter is so proportioned to the capacities of the blowers, that the air will be sufficiently congested in the chamber 16 to cause it to receive the required amount of heat before entering the conduits of the walls.
- Provision is made for effecting results in connection with the bottom of the pool corresponding to those described for the sides and ends. In the drawings a trap or outlet *d* is shown located centrally of the deep end 11 of the pool. The floor 9 is provided with conduits 29 disposed underneath the sections *b* of veneering and communicating with the conduits 12' and 20 of the end walls 13 and 21. A floor plate 30 of terra cotta or the like is disposed in a recess made to receive it in the floor and the concave face 31 of the plate slopes gradually from the plane of the floor surface of the deep end 11 and has a centrally disposed socket 32 in which is arranged a removable cap 33, having slits
- 34 forming fluid passages between the pool and the conduits 29 when the pool is charged with water. The plate 30 is replaceable by a closure plate 35, Fig. 18, for preventing escape of heated air in the process of drying the conduits when the pool is empty. The relatively narrow webs 36, which terminate in depending bases 37 and which are arranged in spaced relation on the underside of floor plate 30, provide a double series of conduits 38-39, which are disposed at right angles to each other and intercommunicate and further communicate with the conduits 29. This construction obviously effects a circulation of heated air through the conduits 29 in drying the joints between the sections *b* of veneering and also permits of maintaining a hydrostatic pressure balance on the floor 9, when the pool is charged with water.
- The sections *b* of veneering which cooperate with the retaining wall 5 to provide the conduits 6 may be formed in various shapes. In one embodiment, shown in Figure 7, the sections *b* are of glazed terra cotta, each section being a channeled structure as indicated by 40. In this construction the side or body 41 is glazed and provides the facing. The side edges of the top 42 and bottom 43 abut against the retaining wall 5 and the end edges of these parts and those of the body abut against the corresponding edges of adjacent tile. The openings 7' in the top and bottom are in alignment and are so arranged that when the sections in one course break joints with those in adjacent courses, above or below, the openings 7' of the various courses will be substantially in vertical alignment. In the modified form, shown in Figure 10, the body 44 is provided with obliquely disposed webs 45-46. This form of section may be used to provide the diverging or oblique conduits 12 of end wall 13, which serve to connect the conduits 6 of the side walls with the vertical ducts 17. The form of section shown in Figure 9 is channeled and constructed like the form shown in Figure 7, except that the side pieces 47-48 are disposed at the ends of body 49. This form of section is employed for the vertical conduits 12', which connect the ducts 17 with the conduits 29 of the floor 9.
- The webs of the form shown in Figure 8 and the pieces 47-48, shown in Figure 7, will be understood as being attached to the retaining wall 5 by cement or equivalent fastening means. The conduits 12' formed by the sections illustrated in Figure 9 are staggered because of the sections *b* in adjacent rows breaking joint. In the embodiment shown in Figure 2, the arrangement is such that certain of the conduits 12 supply the extensions of ducts 6 in end wall 13 in addition to directing heated air into the

conduits 29. This arrangement, of course, will be considered as being only illustrative, it being obvious that the results shown in connection with Figure 2 may be had with 5 other arrangements of sections or by making minor mechanical changes in the construction of the forms of sections shown in Figures 8 and 9. The lateral extensions 14 of the ducts 6 may, as shown in Figure 2, be 10 constructed so as not to communicate one with the other, in which event the openings 7' described in connection with the sections forming the side wall will be omitted.

The sections *b* forming the veneered surface 15 of the floor 9 may be constructed similarly to the sections forming the side walls so that the conduits 29 may communicate one with the other. The floor 9 of the area in the deep portion of the pool surrounding 20 the floor plate 30 is laid by preference in sections disposed at right angles to each other and joining on diagonal lines 50 extending to the corner of the deep portion. Right and left angular shaped sections 51 25 and 52 are employed for connecting the sections on the lines 50 and are constructed so as to form continuations of the conduits of the floor and the conduits 38 and 39 of the floor plate, which as shown in Figure 4 communicate 30 with the mouth 53 of the trap in the base of which is disposed a strainer 54 preferably fastened to a collar 55 attached to the central waste pipe 56, the valve of which is not shown. With this construction 35 the water from the conduits of the floor may be readily drained when the tank is empty.

In the form shown in Figure 15 the veneering is formed of hollow section corresponding 40 in cross sections substantially to the sections 40, except that their upper sides 57 have depending flanges 58 which in cooperation with the lower sides 59 provide openings disposed in the rear of the courses 45 of enameled brick 60. Aligning openings 62 are formed in the portions 57 and 59 and thereby establish communication between the various rows of conduits 63. It will, of course, be understood that with this construction 50 the conduits 63 are relatively rough in construction as distinguished from the conduits 6. In this construction combined tile and enameled brick may be employed for any of the purposes previously 55 described in connection with Figures 1 to 5; the conduits 63 being constructed and disposed so as to admit of the circulation of heated air through the space behind the brick 60 or to provide drainage for water 60 seeping through the retaining wall 64. The conduits may also serve as a means for admitting water in the event that the bricks are employed as a veneering for the surface of a swimming pool.

65 Although I have shown and described an

ideal embodiment of my invention it is obvious that the same is susceptible of numerous uses and arrangements of parts together with modifications in structure of the sections of veneering not herein described. It is, therefore, understood that I reserve the right to employ equivalent constructions and arrangements within the scope of the appended claims.

I claim:

1. A chamber comprising walls each containing a retaining portion and a facing therefor and said facing consisting of intermediate rows of sections of terra cotta, tile, or the like, formed with intercommunicating channels and having their side edges secured to one face of the retaining wall, and upper and lower rows of sections formed with channels communicating with the channels of the intermediate rows and with the space enclosed by the chamber.

2. A space enclosing structure comprising vertical walls each composed of a main body portion and a facing on the inner side of the main body portion, said facing at one portion of the structure having vertically disposed conduits and at other portions of the structure to provide substantially horizontal conduits communicating with the vertically disposed conduits, and means for circulating a fluid through said conduits between the facing and the main body of the walls.

3. A space enclosing structure, such as a swimming pool, comprising a floor composed of a main body portion and a facing, said facing being constructed of channel sections providing intercommunicating conduits between the facing and the main body of the floor, drainage means in communication with said conduits, a perforated member in said facing for allowing the contents of the pool to flow outwardly to the drainage means, said member being removable to enable it to be replaced by an imperforate member in order to permit the conduits to be dried by the circulation of a moisture-absorbing fluid through the conduits.

4. A swimming pool comprising walls and a floor, each composed of a main body portion and a facing, the facing of the walls being constructed of channel sections providing conduits permitting circulation of water vertically and horizontally between the facing and the main body of the walls and the facing of the floor being also constructed of channel sections providing conduits located between the facing and the main body of the floor and communicating with the conduits in the walls, means for draining the pool, and means for establishing fluid communication between the conduits of the floor on the one end and the interior of the pool and the drainage means on the other, so that when the pool is filled

with water, the water is allowed to attain the same level in the conduits between the facing and the main body of the walls of the pool as in the interior of the pool, and when the pool is emptied, the water between the facing and the main body of the walls of the pool is allowed to flow freely from the

pool so as to cause a hydrostatic balance to be constantly maintained on the sides of the facing.

10

In testimony that I claim the foregoing as my invention, I have signed my name hereunto.

JOHN FRANCIS BOORAEM.
